BRAKE DRUM

Ludger E. La Brie, South Bend, Ind., assignor to
Bendix Aviation Corporation, South Bend, Ind.,
a corporation of Delaware

Original application February 20, 1933, Serial No.
657,693. Divided and this application Septem-
ber 12, 1935, Serial No. 40,292

6 Claims. (CL 188—218)

This invention relates to brakes, and is illus-
trated as embodied in brake drums having liners
cast therein and constructed to cooperate with
a backing plate to keep water and dirt out of the
brake.

5 The seal desired, between the drum and back-
ing plate, is in part achieved by flaring the drum
and forming the backing plate with a flange gen-
erally edge to edge with respect to the flared
part of the drum, and arranging the liner to ex-
tend and bridge across the joint so formed, to
give a baffle effect. Preferably the space so
provided between the liner and the flange on the
backing plate is utilized by providing an external
rib on the liner, thus giving an additional baffle
10 effect.

10 The above and other objects of the invention,
including various novel combinations of parts
and desirable particular constructions, will be
apparent from the following description of the
illustrative embodiments shown in the accom-
panying drawing, in which:

15 Figures 1 and 2 are side elevations of two
drums, with their backing plates, partly broken
away in radial section, and each showing a dif-
ferent embodiment of my invention.

20 In Figure 1, the drum is shown at 10, and is
provided with an external cylindrical flange 12
continued as a flared portion 14 which in turn is
30 integral with a cylindrical edge portion 16 of
larger diameter than the flange 12. The drum
is preferably pressed from sheet steel.

25 Seated within the flange 12, and welded or
otherwise secured thereto, is a sheet-steel ring
18 having a flange 20 seated against (and if de-
sired spot-welded or otherwise secured to) the
35 head of the drum, and which carries cast iron
material 22 preferably centrifugally cast therein.
The ring 18 and cast iron 22 form a liner which
40 is the actual friction part of the drum. The liner
extends beyond the edge portion 16 of the drum,
and is preferably there provided with a rib 24
45 formed in the ring 18 and into which the cast
iron 22 extends.

50 The drum is, when in use, associated with a
backing plate or the like 26 having a peripheral
flange 28 which extends across the rib 24 and is
arranged in close edge to edge relation to the
portion 16. It will be noted that the liner 18—22
55 extends and bridges across the joint between
the drum and the backing plate.

The construction of Figure 2 differs from that
of Figure 1 principally in that a flared conical
part 14 replaces the flaring portion 16 and the
cylindrical portion 16.

While two illustrative embodiments have been

described in detail, it is not my intention to limit
the scope of the invention to those embodiments,
or otherwise than by the terms of the appended
claims. The present application is a division of
my application No. 657,693, filed February 20, 5

I claim:

1. A brake comprising a drum having a gen-
erally cylindrical outer flange, a backing plate
at the open side of the drum having a flange
of the same diameter as the edge of the drum
flange and projecting toward and arranged sub-
stantially edge to edge with respect to the drum
flange, and a liner secured in the drum flange
and provided with the braking surface of the
drum and bridging across the annular joint be-
10 tween the two flanges. 15

2. A brake drum having a generally cylindrical
outer flange terminating in an outwardly-flared
extension, and a liner secured in the drum flange
20 and provided with the braking surface of the
drum and having an external rib beyond the edge
of said flange, said extension having a greater
total diameter than said rib.

3. A brake drum having an external cylindrical
flange continued as a flaring portion of greater
25 diameter than said flange, and a liner fitting
within and secured to said flange and continued
beyond the edge of said flaring portion and
which is unsupported by said flaring portion. 30

4. A brake drum having an external cylindrical
flange continued as a flaring portion of greater
35 diameter than said flange, and a liner fitting
within and secured to said flange and continued
beyond the edge of said flaring portion and which
has an external rib of less diameter than said
flaring portion. 30

5. A brake drum having an external cylindrical
flange continued as a flaring portion of greater
40 diameter than said flange, and a liner fitting
within and secured to said flange and continued
beyond the edge of said flaring portion and which
is unsupported by said flaring portion, and which
comprises a steel ring having iron cast on its 45

inner face.

6. A brake drum having an external cylindrical
flange continued as a flaring portion of greater
45 diameter than said flange, and a liner fitting
within and secured to said flange and continued
beyond the edge of said flaring portion and which
is unsupported by said flaring portion, and which
comprises a steel ring having iron cast on its 50

inner face and extending into said rib.
